HIGHWAY CONSTRUCTION

Leo J. Pearce, Olathe, Kans., assignor of one-half
to Lloyd M. Chambers, Olathe, Kans.

Application June 10, 1935, Serial No. 25,843

18 Claims. (Cl. 94—4)

This invention relates to highway construction and has particular reference to that type of road which comprises an upper or wearing surface of a rigid cementitious substance commonly called "concrete highway" and the primary object of this invention is to provide improvements in such a road as will prolong its life by way of preserving the rigid cementitious superstructure because of the ability of the elements in the construction 5 to relieve the upper rigid superstructure of stresses and strains to which it is otherwise subjected when the highway is in use.

One of the important aims of this invention is to provide a highway construction which comprises a number of specially formed and uniquely combined courses, one of which is a pillow-course made up of comminuted material such as sand, gravel or other analogous substance which may be packed or spread to suit conditions, said pillow- 10 course being encased in a suitable envelope or enclosure that is made up of pre-formed sheet material such as heavy paper.

Another object of this invention is the provision of unique and novel means of combining a pillow-course in a highway construction which means includes a case for the pillow-course that may have parts to completely enclose the sand or like material or which may have only members at the longitudinal edges of the highway 15 which serve to confine the pillow-course to a position beneath the rigid cementitious superstructure.

A large number of minor objects which include the unique way of securing together the various 20 parts of the pillow-course case and the novel manner of associating the sheet material with the highway construction will appear during the course of the following specification referring to the accompanying drawings wherein one preferred embodiment of the invention has been illustrated and wherein modifications of the preferred form have been shown.

In the drawings,

Figure 1 is a vertical cross section through a 25 highway construction made to embody the present invention.

Fig. 2 is a fragmentary top plan view of a section of the highway construction, parts being broken away for clearness.

Fig. 3 is an enlarged fragmentary detailed sectional view taken on line III—III of Fig. 2 and illustrating the unique expansion joint which is used in highway construction when the same is made to embody the present invention.

Fig. 4 is an enlarged fragmentary detailed sec-

tional view through one side of the highway construction taken on line IV—IV of Fig. 2.

Fig. 5 is a greatly enlarged fragmentary detailed sectional view taken through the anchor which is employed in one form of the invention. 5

Fig. 6 is a similar view to that shown in Fig. 4 and illustrates a modified form of the invention.

Fig. 7 is a view similar to that of Fig. 6 and shows a still further modification of highway construction, and

Fig. 8 is a vertical cross section through a highway construction which embodies an even further modification of the invention.

Reference to Figs. 1 to 5 inclusive will readily indicate that the highway construction consists 15 essentially of the conventional form rails 10 that extend along the longitudinal sides of the highway construction and upon the subgrade 12 that has been prepared by grading, rolling, or otherwise conditioning so that it will properly receive 20 the component parts of the highway per se. After forms 10 have been placed, the pillow-course is laid upon subgrade 12 therebetween. This pillow-course in the form illustrated in Figs. 1 to 5 inclusive, comprises a continuous lower sheet 14 25 and an upper or cover sheet 16 positioned in the relation shown in Fig. 1. Each of these sheets are substantially continuous but comprises a number of over-lapping strips of heavy paper or the like that extend transversely across the highway construction so that the portions thereof adjacent the ends are in over-lapped relation. In the instance shown in Figs. 1 and 4, lower sheet 14 30 is extended up along the sides of the pillow-course and then inwardly along the top thereof 35 so that the upper cover sheets 16 will over-lap for securing thereto.

The means of securing together the upper and lower sheets 14 and 16 is preferably in the form of a suitable anchor which will not become dislodged after once moved to the operative position. This anchor is shown in Figs. 4 and 5 and may consist of a specially formed nail-like structure having a shank 18 and a head 20 with a pair of pivotally mounted wings 22 thereon 45 which, when outward, upward movement is imparted to the anchor after it has been forced to position, will move outwardly to the positions shown in Figs. 4 and 5 so that the anchor cannot be withdrawn. 50

The pillow-course has a filling of sand or other suitable comminuted material 24 that may be compacted to a suitable density as the said course is laid. Sand has been found highly satisfactory and when it is used a decided cushion effect is 55

presented to the overlying concrete slab 26 that is poured upon the pillow-course in the regular fashion. This upper rigid cementitious superstructure 26 is in the form of a series of sections 5 which have their adjoining ends in substantially abutting relation to form expansion joints detailed in Fig. 3. This expansion joint should consist of a filling of asphalt 28 that is poured into the space between the ends of sections of 10 superstructure 26 and in order to insure longitudinal movement when contraction and expansion occurs, a friction plate 30 is placed beneath superstructure 26 so that it laps the proximal ends of these aforesaid sections. One section of 15 the superstructure 26 is secured to the friction plate 33 as at 32 through the medium of a number of pins or the like while the immediately adjoining section merely rests upon plate 30 so that it will freely move. Plate 30 is depressed into 20 the pillow-course so that its upper face is on the same plane with the upper face of said pillow-course and the lower face of the superstructure 26. This is another important feature of the invention and the employment of a pillow-course as mentioned, will permit such relationship between the parts. In the preferred embodiment of the invention, this pillow-course is of uniform thickness throughout and after rails 10 are removed, the case, which is formed as before mentioned, is strong enough to confine the comminuted material 24 until the shoulders are graded 25 and compacted. Thereafter, the pillow-course is definitely confined and it will serve to equalize pressure, absorb shocks and otherwise function in serving as a preserving course for the rigid superstructure 26.

In some instances it may be desirable to eliminate the continuous upper sheet of material which forms a part of the case for the pillow-course and the side walls of the pillow-course may be strengthened when eliminating such upper sheet as shown in the modified embodiment of the invention illustrated in Fig. 6. When constructing the highway in accordance with this modified form of the invention, rails 40 are placed upon the subgrade 42 in the usual fashion and then the several strips of road paper or the like, are extended transversely across the subgrade 42 in over-lapping relation. In so laying 40 the paper, a bottom sheet 44 is created and a length of the paper is rebent upon itself adjacent the ends so that a wall 46 of double thickness is made. A portion of the material is turned in 45 between filling 48 and superstructure 50 and this inturned portion is likewise made up of two thicknesses of the paper. The end of the paper is disposed between subgrade 42 and layer 44 as illustrated at 52 so that it will be definitely secured. It is desirable in this form of the invention to anchor the inturned double thickness 50 portion of the pillow-course sheet to the superstructure 50 and a number of anchor members 54 in the form of nail-like units may be employed. When they are employed, the heads thereof 55 should be confined between the upper and lower layer of the double thickness portion which is confined between filling 48 and superstructure 50. Obviously when rail 40 is removed, the paper 60 cannot become dislodged and the shoulder is graded and compacted as before.

In the form of the invention shown in Fig. 7, rail 60 is upon subgrade 62 in the usual manner and the paper encasing filling 64 is formed as illustrated. The lower sheet 66 is rebent upon 75 itself to form an inturned portion 68 and a side

wall 70 both of which are double thickness. The upper sheet 72 extends in over-lapping relation with the double thickness inturned portion 68 and an anchor 74, having its head between the two thicknesses of the inturned portion 68 is projected through upper sheet 72 and into filling 64. Obviously the manner of creating this double thickness side wall is susceptible of establishing a very strong and rigid construction that will not become disassembled when rail 60 is removed and the shoulders are being formed. The upper superstructure 76 is laid upon the pillow-course in the regular manner.

Reference to Fig. 8 indicates a manner of associating a pillow-course with a highway construction without the employment of the road paper. In this instance, side rails 80 are placed upon the subgrade 82 and longitudinally extending plates 84 are driven into the subgrade and allowed to overlap rails 80 as illustrated in the left of Fig. 8. Inturned flanges 86 formed on plates 84 are embedded in the rigid cementitious superstructure 88 after the concrete is poured. However, prior to the pouring of the concrete, the comminuted material 90 is laid upon subgrade 82. After the concrete has been poured, rails 89 may be removed and a shoulder 92 graded and compacted in the regular manner. Obviously plates 84 will confine the sand or comminuted material 90 during this shoulder forming operation.

While the quickest manner of laying the sheets 14 and 16 have been illustrated and described, it is obvious that the most efficient and less troublesome way of placing the strips making up the sheets, is to run said strips longitudinally. So placing the strips will allow the concrete to be spread yet not pull the over-lapping strips out of place. The invention contemplates laying the strips forming the pillow-course casing in any suitable manner.

In some forms of construction, the rails or analogous members 10 need not be as high as the combined thickness of the laminated paving. The subgrade may be channeled out to receive 45 the entire pillow-course including the case and filling.

From the foregoing it will be observed that the important component parts of a highway construction embodying this invention include a well 50 prepared subgrade, a pillow-course of comminuted material properly confined, and a rigid superstructure of cementitious material. A number of ways of forming this unique and novel highway construction have been illustrated and described 55 and it is obvious that other ways of making the highway construction might be employed without departing from the spirit of the invention or scope of the appended claims.

Having thus described the invention, what I 60 claim as new and desire to secure by Letters Patent is:

1. A highway construction comprising a sub-grade; a pillow-course of shiftable material and of uniform thickness overlying the subgrade; and 65 a rigid cementitious superstructure resting upon the said pillow-course.

2. A highway construction comprising a sub-grade; a pillow-course of shiftable material and of uniform thickness overlying the subgrade; a 70 case enclosing the pillow-course; and a rigid cementitious superstructure resting upon the said pillow-course.

3. A highway construction comprising a sub-grade; a pillow-course of shiftable material and 75

5 of uniform thickness overlying the subgrade, a pre-formed sheet of material overlying the said pillow-course; and a rigid cementitious superstructure resting upon said sheet and pillow-course.

10 4. A highway construction comprising a sub-grade; a pillow-course of sand of uniform thickness overlying the subgrade; a sheet of material interposed between the subgrade and pillow-course extending upwardly along the sides of said pillow-course to confine the material thereof; and a rigid cementitious superstructure resting upon said pillow-course.

15 5. A highway construction comprising a sub-grade; a pillow-course of sand of uniform thickness overlying the subgrade; a sheet of material interposed between the subgrade and pillow-course to confine the material thereof; and a rigid cementitious superstructure resting upon said pillow-course; said sheet of material extending inwardly from the longitudinal edges of the pillow-course and superstructure and between the two whereby to hold the longitudinal marginal portions of the pillow-course against displacement.

20 6. A highway construction comprising a sub-grade; a pillow-course of comminuted material and of uniform thickness overlying the subgrade; a rigid cementitious superstructure resting upon said pillow-course; and a case for said pillow-course comprising a sheet of heavy paper, disposed between the subgrade and pillow-course, having upturned portions along the sides of said course and inturned margins extending between the pillow-course and superstructure, and another sheet of heavy paper disposed between the said pillow-course and superstructure, overlapping and secured to the inturned margins of the said first mentioned sheet.

25 7. A highway construction comprising a sub-grade; a pillow-course of comminuted material and of uniform thickness overlying the subgrade; a rigid cementitious superstructure resting upon said pillow-course; and a case for said pillow-course comprising a sheet of heavy paper, disposed between the subgrade and pillow-course, having upturned portions along the sides of said course and inturned margins extending between the pillow-course and superstructure, and another sheet of heavy paper disposed between the said pillow-course and superstructure, overlapping and secured to the inturned margins of the said first mentioned sheet; the means of securement between said overlapping sheets of heavy paper being anchored in the comminuted material of the said pillow-course.

30 8. A highway construction comprising a sub-grade; a pillow-course of comminuted material and of uniform thickness overlying the sub-grade; a rigid cementitious superstructure resting upon said pillow-course; and a case for said pillow-course comprising a sheet of heavy paper, disposed between the subgrade and pillow-course, having upturned portions along the sides of said course and inturned margins extending between the pillow-course and superstructure, and another sheet of heavy paper disposed between the said pillow-course and superstructure, overlapping and secured to the inturned margins of the said first mentioned sheet, the means of securement between said overlapping sheets of heavy paper extending through the latter and having portions thereof anchored in both the comminuted material of the said pillow-course and in the said superstructure.

35 9. A highway construction comprising a sub-grade; a pillow-course comminuted material overlying the subgrade; a rigid cementitious superstructure resting upon the pillow-course and a sheet of material disposed between the subgrade and pillow-course extending upwardly along the sides thereof and inwardly between the superstructure and pillow-course, said sheet of material being rebent upon itself along the inwardly and the upwardly extending portions thereof to form a double thickness side wall for the said pillow-course.

40 10. A highway construction comprising a sub-grade; a pillow-course comminuted material overlying the subgrade; a rigid cementitious superstructure resting upon the pillow-course and a sheet of material disposed between the subgrade and pillow-course extending upwardly along the sides thereof and inwardly between the superstructure and pillow-course, said sheet of material being rebent upon itself along the inwardly and the upwardly extending portions thereof to form a double thickness side wall for the said pillow-course; the edge of said material extending inwardly between the subgrade and sheet of material to anchor the same in place.

45 11. A highway construction comprising a sub-grade; a pillow-course comminuted material overlying the subgrade; a rigid cementitious superstructure resting upon the pillow-course and a sheet of material disposed between the subgrade and pillow-course extending upwardly along the sides thereof and inwardly between the superstructure and pillow-course, said sheet of material being rebent upon itself along the inwardly and the upwardly extending portions thereof to form a double thickness side wall for the said pillow-course, the portion of said sheet of material extending inwardly between the pillow-course and rigid superstructure having an anchor extending upwardly into the said superstructure.

50 12. A highway construction comprising a sub-grade; a pillow-course comminuted material overlying the subgrade; a rigid cementitious superstructure resting upon the pillow-course and a sheet of material disposed between the subgrade and pillow-course extending upwardly along the sides thereof and inwardly between the superstructure and pillow-course, said sheet of material being rebent upon itself along the inwardly and the upwardly extending portions thereof to form a double thickness side wall for the said pillow-course, the rebent portion of said sheet of material extending between the pillow-course and rigid superstructure having an anchor extending upwardly through the uppermost layer of material into the said superstructure.

55 13. A highway construction comprising a sub-grade; a pillow-course comminuted material overlying the subgrade; a rigid cementitious superstructure resting upon the pillow-course and a sheet of material disposed between the subgrade and pillow-course extending upwardly along the sides thereof and inwardly between the superstructure and pillow-course, said sheet of material being rebent upon itself along the inwardly and the upwardly extending portions thereof to form a double thickness side wall for the said pillow-course, the rebent portion of said sheet of material extending between the pillow-course and rigid superstructure having an anchor extending upwardly through the uppermost layer of material into the said superstructure, said anchor having a head disposed between the two layers of said sheet material whereby to preclude

sinking into the said pillow-course as the super-
structure is poured.

14. A highway construction comprising a sub-
grade; a pillow-course comminuted material
5 overlying the subgrade; a rigid cementitious
superstructure resting upon the pillow-course;
a sheet of material disposed between the sub-
grade and pillow-course extending upwardly
10 along the sides thereof and inwardly between the
superstructure and pillow-course; and a sheet of
material disposed between the pillow-course and
superstructure overlapping the portion of the
first mentioned sheet disposed between the su-
15 perstructure and pillow-course, said first men-
tioned sheet being rebent upon itself along the
inwardly and the upwardly extending portions
thereof to form a double thickness wall for the
said pillow-course.

15. A highway construction comprising a sub-
grade; a pillow-course of comminuted material
overlying the subgrade; a rigid cementitious su-
perstructure resting upon the pillow-course; a sheet of material disposed between the subgrade
20 and pillow-course extending upwardly along the
sides thereof and inwardly between the super-
structure and pillow-course; and a sheet of ma-
terial disposed between the pillow-course and
superstructure overlapping the portion of the first
25 mentioned sheet disposed between the super-
structure and pillow-course, said first mentioned
sheet being rebent upon itself along the inwardly
and the upwardly extending portions thereof to
form a double thickness wall for the said pillow-
30 course, said overlapping sheet materials having
an anchor extending through one thickness of
the rebent sheet and through the other sheet
into the said comminuted material of the pillow-
course.

16. A highway construction comprising a sub-
grade; a pillow-course of comminuted material
overlying the subgrade; a rigid cementitious su-
perstructure resting upon the pillow-course; a sheet of material disposed between the subgrade
40 and pillow-course extending upwardly along the
sides thereof and inwardly between the super-
structure and pillow-course; and a sheet of ma-
terial disposed between the pillow-course and
superstructure overlapping the portion of the the
45

first mentioned sheet disposed between the su-
perstructure and pillow-course, said first men-
tioned sheet being rebent upon itself along the
inwardly and the upwardly extending portions
thereof to form a double thickness wall for the
5 said pillow-course, said overlapping sheet mate-
rials having an anchor extending through one
thickness of the rebent sheet and through the
other sheet into the said comminuted material
of the pillow-course, said anchor having a head
10 confined between the rebent portions of the first
mentioned sheet.

17. A highway construction comprising a sub-
grade; a pillow-course of sand overlying the sub-
grade; a rigid cementitious superstructure rest-
15 ing upon the pillow-course; and a case for the
pillow-course comprising a plurality of strips of
paper extending transversely across the high-
way construction between the subgrade and the
pillow-course in overlapped relation; and a plu-
20 rality of strips of paper extending transversely
across the highway construction between the pil-
low-course and the rigid superstructure in over-
lapped relation, the ends of the several strips of
the first mentioned plurality of strips of paper
25 being in overlapped relation with the ends of the
several strips of the second mentioned plurality
of strips of paper adjacent to the longitudinal
edges of said highway construction.

18. A highway construction comprising a sub-
grade; a pillow-course of sand overlying the sub-
grade; a case for the pillow-course confining the
sand to a predetermined position; a rigid ce-
mentitious superstructure resting upon the said
pillow-course comprising a plurality of abutting
30 sections; and an expansion joint formed at the
abutting ends of the superstructure having a fric-
tion plate interposed between the said super-
structure and the case, means for rigidly securing
the plate to one section of the superstructure, and
35 yieldable material interposed between the abut-
ting ends of the sections, the plate extending be-
neath the other section and depressed into the
pillow-course with its upper face in substantially
40 the same plane as the lower faces of the super-
structure sections and the upper face of the case
45 enclosing the pillow-course.

LEO J. PEARCE.
